FORM CLIP

Frederick G. Kugel, Bloomfield, N. J., assignor to
The M. W. Kellogg Co., New York, N. Y., a corporation of Delaware

Application March 20, 1937, Serial No. 132,173

5 Claims. (Cl. 72—122)

This invention relates, in general, to a form clip or brace and is particularly adapted to be used in connection with the protective coating of exposed metal surfaces.

More particularly this invention is adapted to be used in the process of applying coverings of cementitious material to the exposed surfaces of metal structures whether for the purpose of insulating, waterproofing or fireproofing, or for the sake of appearance.

In the art of structural steelwork, although not necessarily limited thereto, it has become a more or less regular practice to plaster the exposed portions of the completed metal structure 15 with a cementitious mixture for the purpose of protecting them from the elements.

As known to those well versed in the art, this is commonly done by a method known as the "Guniting process", or "Guniting". As carried out, 20 this embodies the use of a cement gun through which the mixture is forced by compressed air.

The surface to be coated is first prepared so that the distinctive form and contour of the structure will be preserved in outline after the 25 coating is applied. In other words, the structure is not buried in the cementitious material but is merely covered with a coating a few inches in thickness. The material is usually reenforced by a mesh held firmly in position closely adjacent 30 the metal member.

In order to follow the true line and surface so that every angle, surface, sharp arris and fillet will be clearly delineated, and to insure uniform 35 application of the coating, it is necessary to erect guides or alignment boards known as shooting strips. These are usually thin wood strips or boards which are erected near the line of intersecting or adjacent surfaces. They are used either for the purpose of sighting the true 40 edge line, or for actually molding each corner or arris. Where the surfacing is to be completed by hand they provide a convenient guide for the trowelling operation.

One of the chief difficulties encountered in this 45 type of work has been in connection with the erection of the shooting strips. Ordinarily the only available surface to which they may be attached is the very surface which is to be coated. Since it is impossible to nail the strips to the 50 metal work the common practice has been to weld the head of an ordinary nail to the metal surface with the body portion of the nail substantially normal to the surface. A series of these nails were so disposed at convenient points 55 about the surface and the wooden shooting strip

was impaled on the projecting nails until it was supported in the desired position.

This practice has several disadvantages among which is the difficulty of accurately positioning the shooting strip on the supporting nails so that a true guide line or surface is defined. Another difficulty is encountered in attempting to suitably place shooting strips at corners or the outer edges of flanges and the like.

Hence, one of the principal objects of this invention is to provide a metal clip or bracket adapted to be attached to a metal surface for the purpose of supporting objects therefrom.

Another object is to provide a metal clip or support which may be readily attached to a corner surface for the purpose of suspending or supporting objects therefrom.

Still another and more specific object is to provide a metal form clip adapted to be attached to a metal surface for the purpose of supporting 20 a form or frame a fixed distance from the metal surface.

A further object is to provide a metal clip or support capable of being attached to flat metal surfaces either perpendicularly or at an angle 25 thereto.

A still further object is to provide a metal clip, one end of which is adapted to be rigidly attached to a metal surface and the other end of which is shaped to provide an impaling means 30 upon which an object may be impaled for the purpose of support.

These and other objects are effected by this invention, as will be apparent from the following description and claims taken in connection with 35 the accompanying drawing forming a part of this application, in which:

Fig. 1 is a view in elevation showing a preferred embodiment of the metal form clip adapted for use on either flat or corner surfaces.

Fig. 2 is a view similar to Fig. 1 showing a modified form of clip also adapted for use on flat or corner surfaces.

Fig. 3 is an elevation view of a modified form of clip designed for use on flat surfaces.

Fig. 4 is a view showing a form clip, of the type shown in Fig. 1, positioned on the edge of a metal member.

Fig. 5 is a view in elevation showing a form clip, of the type illustrated in Fig. 1, positioned 50 on a flat metal surface; and,

Fig. 6 is a view showing how the clips may be used to support guide strips for a float board.

In accordance with my invention, I provide, as shown in Fig. 1, a metal strip or plate 11 which 55

is preferably cut from strips of thin metal stock having the desired physical properties.

The ends of the clip 11 are irregularly shaped, which shaping may be done in a single cutting 5 operation or the shaping may be done in subsequent operations.

The lower, or tail end of the clip is formed with a notch 12, the vertex of which is on the longitudinal center line, thus giving the end a 10 fish-tail appearance. As shown in the drawing, the notch 12 is a right angle, which is most desirable for use on corners where the adjacent surfaces meet at a right angle, although for corners having a different angle a corresponding 15 notch angle may be used.

The notching operation results in the formation of two projecting points 13 and 14 which may be bent in either direction along their broadest surface to form feet upon which the 20 clip may rest in an upright position as shown in Fig. 5, or which will give a broad contacting area when held against any surface.

Since the clip is designed primarily to be suspended from metal objects or surfaces, the feet 25 formed by bending the points 13 and 14 may be easily secured to the metal surface by welding. In actual usage this operation may be speedily performed. The workman merely grasps the clip, bends the points 13 and 14 over in either 30 the same or opposite directions with a pair of pliers, holds the clip in position against the metal structure and welds the feet, formed by bending the points over, to the metal surface as illustrated in Fig. 5. A series of these clips may be 35 disposed along the surface at spaced intervals to provide a plurality of supports for the shooting strips.

With the construction of the clip as shown in Fig. 2, it is obvious that only one foot support 40 may be formed since only one point 15 is provided. The types of clip shown in Figs. 1 and 2 when attached to a flat surface form a very rigid and sturdy support.

Fig. 3 shows a clip with a squared end. While 45 this type of clip eliminates the operation of bending over the end points to form feet, and thus may be more readily applied, it requires more welding to give it a degree of sturdiness equivalent to that obtained where the bent over 50 points are used. To secure this clip to the flat metal surface, weld metal is applied along the lower edge.

Where the cementitious coating is to be applied to an irregular surface, such as the corner of a 55 beam or flange, it is sometimes desirable to support the shooting strip at an angle to both surfaces, as is shown in Fig. 4. To do this, the clip is placed on the corner of the structure or workpiece 16 with the corner fitting into the notch 12. Weld metal 17 is then deposited along the 60 intersection of the sides of the notch 12 and the surfaces of the workpiece.

The central portion of the upper end of the clip is extended to form a spike 18, the tip of 65 which is cut to form a flat end 19. To either side of the point 17 are formed shoulders 20 and 21.

In placing the shooting strip 22 in position, it is driven on to the spiked portion 17 until the 70 strip contacts the shoulders 20 and 21. The shoulders act as a stop or guide to maintain the distance between the workpiece 16 and the shooting strip substantially uniform, so that an even layer of material may be applied in the 75 "Guniting" operation.

When a plurality of such clips are placed along the edge of a metal surface to support a shooting strip, as shown in Fig. 4, the outer corners of the clip shoulders may be used to sight the imaginary finish line. By applying the cementitious material on both surfaces until the sides of the clip are covered, a bevel edge is formed on the corner of the finished structure. This beveled edge is as wide as the width of the clip.

After the coating has been applied and has 10 solidified, the shooting strips are removed leaving the spike 17 projecting from the beveled edge of the coated surface. The spikes may be left protruding, or may be clipped off or bent over 15 flush with the beveled surface.

The tip portion of the spike 17 is made blunt 20 in order to decrease its tendency to split the shooting strips when the latter are of thin wood material, as is commonly the case. However, with different materials or under certain conditions it is contemplated that pointed spikes may be used.

It will be noted that the portions of the shoulders 20 and 21 immediately adjacent the base of the spike 17 are cut out below the shoulder line 25 at 23. The purpose of cutting away in this manner is to provide a minimum of exposed metal surface when the shooting strip is removed.

Where it is desirable or necessary to finish 30 with a square, instead of a beveled, edge, the coating material may be directly applied in that fashion by sighting to the point where the imaginary center line of the clip intersects the under surface of the shooting strip. This point, which 35 is designated 24 in Fig. 4 is more easily located because of the cut away portions 23, it being merely necessary to estimate the center of the base portion of the spike 17 and to deposit the material up to that point. Obviously when the 40 shooting strip is removed not only the spike 17, but also portions of the shoulders 20 and 21 will project through the surface of the coating. These may all be clipped off.

Fig. 6 shows a method of using the clip in 45 which none of the metal parts will be visible after the coating is applied, and in which mechanical levelling means may be employed to obtain a smooth flat surface. The clip is secured to the corner of the workpiece, as before, 50 and a narrow strip of wood 25 is impaled on the spike 17.

The coating material is then deposited to the outer edge of the wood strip. When this has 55 been done to both sides and the material has set, the wood strip is pulled off the spike, thus leaving a channel in the cementitious material. This channel is then filled with the coating material and trowelled to form either a bevelled or 60 a sharp corner.

To coat a surface having two opposite edges, the clips are placed and welded, as shown, on the opposite corners, the wood strips 25 are driven onto the spikes 17, and the cementitious material is sprayed on the metallic surface to a 65 depth sufficient to cover the outermost corner of the wood strip 25. A "float board" 26, such as is commonly used in smoothing and levelling cement work, may then be slid along the edges of the wood strips to trim off the excess of coating material. In this way a flat, level surface is 70 assured.

From the foregoing it will be observed that I have devised a simple and efficient means for attaching forms to metal structures which not 75

only supports the same in any desired position but also serves as a guide means to insure uniform application of the cementitious coating.

While this invention has been shown in but three forms, it will be apparent to those skilled in the art that it is not so limited but is susceptible to various other changes and modifications without departing from the spirit thereof, and it is desired therefore that only such limitations shall be placed thereon as are imposed by the prior art or are specifically set forth in the appended claims.

I claim:

1. A form clip adapted to be welded to metal structure members for the support of forms or guides in spaced relation thereto comprising a flat body of weldable material having one end extended longitudinally to form a spike adapted for limited penetration into the form or guide, and the opposite end cut irregularly to provide extended portions bendable transversely of the plane of said body to form feet adapted for engagement with the surface of the structure member for the purpose of welding thereto, the sides of said extended portions being formed to engage in abutting relation the adjacent surfaces at the corners of said structure members.

2. A form clip adapted to be welded to metal structure members for the support of forms or guides in spaced relation thereto, comprising a main body portion of substantially thin weldable material having one end adapted for limited penetration into said form for rigid engagement therewith, and the opposite end notched to form a pair of extending members, the sides of said notch being adapted for abutting engagement with the sides adjacent the edges of said structure members, said extending members being readily bendable transversely of said main body portion to form a substantially broad base which when placed in abutting relation to a surface of said metal structure member provides an extensive contacting area for the purpose of welding.

3. A form clip adapted to be welded to metal structure members for the support of forms or guides in spaced relation thereto comprising a flat sheet metal body having part of one end extended longitudinally to form a flat-endspike,

the unextended portion forming a shoulder to limit the penetration of said spike into the form or guide, the opposite end of said body being irregularly extended to form a portion bendable transversely of the plane of said body to provide a foot which when placed against a surface of the form offers a substantially broad contacting surface for the purpose of welding, the foot end of said body having flat edge surfaces extending transversely relative to the longitudinal axis of said spike.

4. A form clip adapted to be welded to metal structure members for the support of forms or guides in spaced relation thereto comprising, a flat body portion of weldable material having one end extended longitudinally to form a spike adapted for limited penetration into said form or guide, the tip of said spike being flattened to minimize its splitting action when driven into the form or guide, and the opposite end having an irregular extension transversely bendable from the plane of said flat body to form a foot adapted to be welded to a flat surface of said metal structure member, a side of said extension in its normally unbent position being transverse relative to the longitudinal axis of said spike.

5. A form clip adapted to be welded to metal structure members for the support of forms or guides in spaced relation thereto comprising a flat sheet metal body having a longitudinally extending spike portion at one end thereof, said spike being flat at the end and having shoulder portions at its base which limit its penetration into the form or guide, said shoulders being raised at their outer ends so that a portion of the spike will be visible without the form or guide; the opposite end of said metal body being irregularly extended to provide portions bendable transversely from the plane of said body to form feet adapted to engage and be welded to the surface of the metal structure member, the edges of said irregularly extended portions presenting flat surfaces transverse relative to the longitudinal axis of said spike whereby the latter end of said clip is adapted for abutting engagement with the edges of said structure members.

FREDERICK G. KUGEL.
